UNITED STATES PATENT OFFICE.

GEORGE D. GREEN, OF ROCHESTER, NEW YORK, ASSIGNOR TO JAMES H. SAGER, OF SAME PLACE.

DESIGN FOR A FRAME FOR MOTOR-CYCLES.

SPECIFICATION forming part of Design No. 33,745, dated December 18, 1900.

Application filed November 2, 1900. Serial No. 35,300. Term of patent 14 years.

To all whom it may concern:

Be it known that I, GEORGE D. GREEN, a citizen of the United States, residing at Rochester, in the county of Monroe and State of New York, have invented and produced a new and original Design for Frames for Motor-Cycles, of which the following is a specification, reference being had to the accompanying drawings, forming part thereof.

10 My design relates to frames for motor-cycles; and it consists in the general shape or configuration of the frame, and particularly of the rear portion thereof.

Figure 1 is a perspective view of a frame 15 constructed in accordance with my design, and Fig. 2 is a side elevation thereof.

The frame is composed of the head 1, from which extends the horizontal top bar or tube 2 and the rearwardly and downwardly extending bar or tube 3, terminating in the

crank-hanger 4. Extending upwardly from the latter to the end of the tube 2 is a central brace or seat-post 5. The upper fork members 6 extend rearwardly and downwardly from the upper end of the post 5, diverging 25 from the center of the brace, and at their lower ends join the rear ends of the lower fork members 7. The lower fork members 7 extend slightly upward at their forward ends, as shown, to the crank-hanger. Between the 30 upper and lower fork members are the additional members 9, joined to the central brace 5.

I claim—

The design for a frame for motor-cycles substantially as herein shown and described. 35

GEORGE D. GREEN.
